UNITED STATES PATENT OFFICE.

FREDERICK KOSKUL, OF ST. LOUIS, MISSOURI.

FABRIC FOR VENEERS.

SPECIFICATION forming part of Letters Patent No. 288,453, dated November 13, 1883,

Application filed October 5, 1882. (Model.)

To all whom it may concern:

Be it known that I, FREDERICK KOSKUL, a citizen of the United States, residing at St. Louis, in the county of St. Louis and State 5 of Missouri, have invented a new and Improved Fabric for Veneers, of which the following is a specification.

My invention consists, first, in a veneer made of transparent varnish; second, in a veneer 10 made of transparent varnish, with a foundation of paper, linen, or other like supporting or sustaining material, and upon which the gluing or cementing material may be applied; third, in a veneer made of transparent var- 15 nish, and with a foundation of destructible paper; and, fourth, in a veneer of varnish and destructible paper, and with ornamentation on its varnish-surface or between layers of varnish, which ornamentation stands in rear 20 of the varnish-surface, which is the exposed one when the veneer is applied to an object.

The veneering material made in accordance with my invention constitutes an article of manufacture or trade which is brilliant in itself, and which is produced by laying varnish upon the foundation or sustaining material in any of the modes known in the arts, and drying or baking the varnish by any of the known methods, and the said article of manufacture 25 serving to protect while it exhibits the ornamentation, which is placed either upon it, or between layers of varnish, or behind the veneer and upon the article veneered. The ornamentation of the varnish-veneer is effected 30 with either a brush, stencil-plates, die-blocks, or rollers, or by any other of the known ways; and this ornamentation may be either upon the outer varnish-surface or between layers of varnish, or it may be placed upon the surface 35 upon which the improved veneer is to be applied. In all cases the veneering material forward of the ornamentation is made of transparent varnish, and the ornamentation is clearly seen through the same. Any known paint 40 or substance used for ornamentation may be adopted.

My present invention differs from the compound varnish and pigment veneer for which I applied for a patent on June 30, 1882, it enabling me to make a veneer of transparent varnish which may be ornamented without mixing or compounding the ornamenting ma-

terial with the substances of which the varnish is composed. The veneer which is produced in accordance with my invention can be 55 preserved in a flexible condition for a sufficient length of time, and it consists of a sufficiently voluminous body, while possessing toughness, to stand handling while being sold and applied, and to permit scraping and rubbing after being glued or cemented to the surface for which it is intended.

In the accompanying drawings an illustration of my invention is shown, Figure 1 being a vertical section of a piece of varnish-veneer without foundation or sustaining-paper and without ornamentation. Fig. 2 is a similar section of the same with foundation or sustaining paper. Fig. 3 is a similar section of same with destructible paper on one of the 70 varnish-surfaces and with ornamentation on the other. Fig. 4 is a section of Fig. 3 as applied to either a wall, chair-back, or other article. Fig. 5 is a section of my improved veneer with destructible foundation-paper on 75 one varnish-surface and with ornamentation between layers of varnish. Fig. 6 is a front view of a piece of the veneer shown in Fig. 3 as applied, and with a portion of the destructible paper removed; and Fig. 7 is a front view, 80 similar to Fig. 6, but with another design of ornamentation, and with all of the destructible paper removed.

A in the drawings designates the varnish-veneer; B, the ornamentation on one of its 85 varnish-surfaces; C, the foundation-paper, and D a wall or other object. If the ornamentation is placed between layers of varnish, the paper foundation C may be of strong material—such as tough paper, light linen, or 90 cotton—and the sizing of glue or material for holding the veneer to the wall or other place may be applied directly upon this paper or foundation material C; but if the ornamentation is on the surface of the varnish-veneer, 95 then this foundation-paper C will be made of destructible material—that is, for instance, paper prepared with either a coating of glue or other substance which will insure its ready destruction or removal by the application of a wet sponge to it. This destructible paper foundation will also be employed when the ornamentation is applied upon the wall or 100 article of furniture, and afterward covered

with the transparent veneer, provided the varnish-veneer is not manufactured without any foundation or sustaining material other than its own constituent elements, in which latter case the transparent veneer would be applied directly over the ornaments, and nothing further done but dressing up in any suitable manner, and when not baked a thin finishing-coat of varnish may be employed for finishing the surface.

I find that the best and most desirable article is produced in the following manner: Take paper prepared with a coating of glue, or its equivalent substitute, and apply one or more coats of transparent rubbing-varnish to the paper, and then either dry or bake the varnish by artificial heat. The baking of the varnish is not absolutely necessary. Veneer made in this way is not very liable to crack, and when applied to surfaces the glue or other sizing used for securing it to the wall or other object will fill up all interstices and irregular portions of the surface. The film-like structure of the veneer, together with its brilliant and transparent character, renders the ornamentation prominent and perfectly visible to the eye, notwithstanding these ornaments are at the back surface of the veneer when applied as shown in Fig. 4, or between layers of varnish when applied as in Fig. 5.

I would state that the foundation-paper, whether of destructible or indestructible material, is not absolutely necessary; but for facilitating the pasting of the veneers upon walls and other objects, and the manufacture of the veneers, especially by machinery—such as rollers, for instance—and also for strengthening and rendering the veneer less liable to crack or break in handling, and for receiving the cementing material, this foundation-paper subserves a very important office.

The varnish-veneer protects the ornamentation from injury while the articles of furniture or walls or any other objects to which it may

be applied are being either rubbed down, 45 scraped, or cleaned.

I am aware that veneer of natural woods, celluloid, prepared paper, metal foil, and the like are common; but neither of these is, of itself, brilliant, nor can either of them be employed, as I believe, in a manner so practical or for so manifold a purpose, and so differently in design, and with such brilliancy of presentation as my improved varnish-veneer. I contemplate employing my improved varnish-veneer in all of the arts to which it may be applicable as a means of finish, decoration, or ornamentation.

What I claim as my invention, and desire to secure by Letters Patent, is—

1. The described veneer as a new manufacture, having its body formed of transparent varnish, substantially as set forth.

2. The described veneer with transparent varnish body, and provided with a foundation 65 of paper or like sustaining material, substantially as and for the purpose described.

3. The described varnish-veneer, its body being of transparent varnish and its foundation of destructible paper, substantially as 70 and for the purpose described.

4. The described veneer, having its body formed of transparent varnish, and having its ornamentations in rear of the varnish-surface, which is the exposed surface after the veneer 75 is applied to an object, substantially as and for the purpose described.

5. The new manufacture herein described, consisting of a veneer having its body formed of transparent varnish, and applied on a de-80 structible foundation of paper, and its ornaments applied in rear of the exposed varnish-surface of the veneer, substantially as described.

FREDERICK KOSKUL.
